EUGENE FULLER, OF PROVIDENCE, RHODE ISLAND, ASSIGNOR OF THIRTY ONE-HUNDREDTHS TO CHARLES A. GAUDETTE, OF PROVIDENCE, RHODE ISLAND.

ATTACHMENT FOR BOOTS AND SHOES.

1,087,361.

Specification of Letters Patent.

Patented Feb. 17, 1914.

Application filed September 30, 1910. Serial No. 584,648.

To all whom it may concern:

Be it known that I, EUGENE FULLER, a citizen of the United States, residing at the city of Providence, in the county of Providence and State of Rhode Island, have invented certain new and useful Improvements in Attachments for Boots and Shoes, of which the following is a specification, reference being had therein to the accompanying drawing.

Devices adapted to be worn beneath the tread portion of boots and shoes and which do not extend the full length thereof, such as rubber half-soles or ice creepers, are impracticable or objectionable unless positively and securely attached.

My invention relates to attachments of this character having improved means for securing them in position for use.

20 The invention is illustrated as including an impervious, resilient half-sole because it is especially adapted for the protection of the tread portions of boots and shoes forward of the shank.

25 One of the objects of the invention is to provide improved means for firmly gripping the attachment to the tread portion of a boot or shoe which it is to protect.

30 A further object of the invention is to provide improved means for uniting the clasp or gripper with the rubber portion when the invention is embodied in a rubber sole protector.

To these ends the invention consists in 35 the construction and combination of parts substantially as hereinafter described and claimed.

40 Of the accompanying drawing:—Figure 1 is a side elevation of a shoe having my invention in one of its embodiments applied to the fore part of the sole of the shoe, a portion of the attachment being in section. Fig. 2 is a perspective view of the attachment but omitting the toe portion thereof, a 45 portion of the lining being broken away to show the metallic parts of the attachment. Fig. 3 represents a section on line 3—3 of Fig. 2. Fig. 4 represents a section on line 4—4 of Fig. 2. Fig. 5 is an under plan view 50 of the shank end of the attachment and showing the gripping members in the positions which they occupy when the jaws are contracted. Fig. 6 represents a section on line 6—6 of Fig. 5. Fig. 7 represents a section on 55 line 7—7 of Fig. 4. Fig. 8 represents a sec-

tion on line 8—8 of Fig. 5, the full lines indicating the relative positions of the parts when the jaws are opened, the dotted lines representing the same positions which they occupy in Fig. 5. Fig. 9 is a perspective view 60 of the lever of the gripping mechanism.

Similar reference characters indicate the same or similar parts in all of the views.

In the embodiment of the invention illustrated, the main part of the attachment consists of a protector for the fore part of the sole of a shoe. For convenience of illustration the bottom surface is not shown as roughened, but it will be readily understood that rubber half-soles are usually corrugated to aid in preventing them from slipping, and if said corrugations were to consist of metal projections, the attachment would serve as what is called an ice-creeper. The specific structure shown herein, however, embodies a rubber layer 10, an inner sole 11 and a lining 12. This portion of the attachment has flanges 13 to embrace the edges of the sole *a* of the shoe. The edge of the flange 13 is preferably thickened to form 75 a bead 14, said flange and bead extending around the sides and tip of the toe of the shoe sole as clearly indicated in Fig. 1. This part of the attachment, whether a rubber half sole or an ice creeper, must for 80 practical purposes be firmly secured at the end opposite the toe portion, and I will now proceed to describe the gripping members 85 which have jaws to grip the edges of the shank portions of the shoe sole.

The main plate 15 has one edge formed with one or more slots 16 as best indicated in Fig. 5. The reason for making two slots in line with each other is so as to leave a connecting web of metal between the front 90 bar 17 of the plate and the main portion of said plate. A divided strip 18 preferably of some strong fabric, is passed around the bar 17 through the slot or slots 16 and the two ends of said strip then cemented between the 95 members 11 and 12 as best shown in Fig. 4. Since of course the members 10, 11 and 12 are all cemented tightly together this structure provides for a durable and reliable connection between the rubber half sole and 100 the gripping device.

The plate or member 15 is bent upwardly at one end to form a jaw 19, and adjacent to said jaw it is cut out and bent outwardly and twisted to form a shouldered stud 20 110

which co-acts with a slot in the lever as hereinafter described to lock the lever in operative or gripping position. The other end of the plate member 15 is bent downwardly and 5 provided with side projections to form a T-shaped stud 21 on which the adjustable jaw member presently described is guided. At an intermediate portion, the plate member 15 is cut out and bent to form an ear 22 to 10 which ear the lever presently described is pivoted, (see Fig. 8).

The plate 23 is bent upwardly at one end to form a jaw 24 to coöperate with jaw 19 in clasping the shank portion of a shoe sole. 15 This adjustable jaw member 23 is formed with a slot 25 to guide it on the stud 21 when being adjusted. Said plate or member 23 is also formed with a plurality of transverse slots 26 through either one of 20 which the lever 27 may pass, said lever being pivoted at one end to the fulcrum ear 22. Of course the normal distance apart of the two jaws will be varied according to which slot 26 receives the lever 27. Said 25 lever 27 is formed with lateral ears 28 (see Fig. 9) which extend over the member 23 at the ends of the slot 26 through which the lever passes, so that when said lever is in the released position, as illustrated in Fig. 30, said ears 28 will still retain and prevent the free end of the jaw member 23 from dropping too far so that said jaw member may be readily carried back to its dotted or closed position by a further movement of 35 said lever. The lever 27 is formed with a T-slot 29 and adjacent the transverse portion of said slot the metal is depressed as at 30 (see Figs. 6 and 9).

When the lever 27 is carried from the position shown by full lines in Fig. 8 to the 40 position indicated by dotted lines in that figure, the curved portion of said lever acts upon the side of the slot 26 through which said lever passes so as to forcibly draw the 45 jaws 19, 24 toward each other to firmly grip the edges of the shank portion of the shoe sole. During the last portion of the movement of the lever 27, the longitudinal portion of the T-slot 29 passes over the stud 20. 50 The lever 27 is constructed of somewhat resilient metal, and it is so shaped that some little pressure will be required to carry it to the position indicated by dotted lines in Fig. 8, after which movement the lever is 55 shifted slightly sidewise so that the shank of the stud 20 passes along the transverse portion of the T-slot 29 and the shoulders of said stud 20 will slip into the depressions 30. Therefore the lever 27 will be securely 60 locked in place and the jaws can not be separated so as to remove the attachment from the shoe sole excepting by releasing the depressions 30 from the shoulders of the stud 20, and then moving the lever 27 slightly 65 laterally to release it from the stud 20 to

70 permit it to be opened to the full line position in Fig. 8. The lever is formed with shoulders 31, see Fig. 9, which engage the inner side of jaw member 23 to positively separate said member 23 from the member 15 so that continued movement of the lever will slide member 23 to separate the jaws. In Fig. 9 is shown the aperture 32 through which the fulcrum ear 22 of jaw member 15 passes.

75 The inner faces of the jaws 19, 24 are preferably formed with spurs 33 to engage the edges of the shank portion of the shoe sole. Said spurs, as shown in Fig. 7, point in a direction toward the slot 16 and consequently point in a forward direction or, in other words, in such direction as to prevent the gripping portion of the attachment from being pulled or slid forwardly toward the toe of the sole. Sometimes the edges of that portion of the shank which is gripped are so nearly parallel that even when a correct adjustment of the gripping members has been made, the jaws might slip along the sole so as to release the entire attachment. 80 The spurs 33 serve to firmly hold the gripping members of the attachment in the longitudinal position where they are clamped.

85 A portion of the flexible part of the device extends rearwardly above the clamping mechanism and consequently is bound firmly against the under surface of the shoe shank when the device is in place, as shown in Fig. 1. In the particular embodiment of the invention illustrated the lining 12 is, as is usual with rubber half-soles, made of waterproof textile material. This layer or lining 12 is longer than the inner sole 11 and sole 10 so as to provide a rear end or edge which, 90 in practice, may be cemented down upon the upper face of the main plate 15. Cement will serve for this purpose, because in use, there is no tendency to pull the rear flap or layer of the lining 12 away from the upper 95 face of plate 15. When the attachment is secured to a bottom or shoe sole, the same act which contracts the jaws serves to press the plate 15 so firmly upward as to clamp the rear end of this flexible portion of the 100 attachment against the under surface of the shoe shank and prevent the entrance of moisture. Of course the flange 13 protects the rest of the shoe sole, and therefore my invention serves the additional function of 105 rendering the sole protector more effective in excluding moisture than is the case with rubber half-soles which have no means for binding their rear edges snugly against the 110 under surface of the shoe shank.

115 It will now be seen that I have provided an attachment for boot and shoe soles shaped at one end to engage the toe end of the sole, the other end of the attachment being provided with two relatively movable jaw 120

members adapted to engage shank portions of the sole, a lever being so connected to one jaw member and engaged with the other jaw member as to forcibly clamp the jaws in place when the lever is being moved from the full line position to the dotted line position indicated in Fig. 8. And the lever is then locked so that it will be held firmly in place. Owing to the connection of the metal portions of the attachment with the flexible sole covering portion, by means of the loops in the attaching strip 18 which is cemented to the fabric portion of the device, the whole attachment can be stretched and attached without liability of the metal portion being pulled away from the rest of the attachment owing to any strain in use due to forward or backward slipping of the foot of the user.

I claim:

1. A boot and shoe sole attachment having a portion at one end to engage the toe end of the sole and having at the other end two slidably connected jaw members to engage shank portions of the sole, one of said members having a slot, a lever passing through said slot and pivotally connected to the other jaw member to forcibly clamp the jaws in place, and locking mechanism for holding the lever in place.

2. A boot and shoe sole attachment having a portion at one end to engage the toe end of the sole and having at the other end two slidably connected jaw members to engage shank portions of the sole, one of said members having a plurality of transverse slots, a lever passing through one of said slots and pivotally connected to the other jaw member to forcibly clamp the jaws in place, and locking mechanism for holding the lever in place.

3. A detachable sole protector for shoes provided with a flexible inner sole having a

portion at one end to engage the toe end of the shoe sole, a slotted gripping device at the rear end of the protector having jaws 45 for clamping and securing said protector to the shoe shank, and an attaching strip of flexible material passing through said slotted portion and doubled over and secured to the inner sole of said protector to secure 50 said clamp to said protector.

4. A detachable sole protector for shoes provided with a flexible inner sole having a portion at one end to engage the toe end of the shoe sole, a slotted gripping device at 55 the rear end of the protector having jaws for clamping and securing said protector to the shoe shank, an attaching strip of flexible material passing through said slotted portion and doubled over and secured to the 60 inner sole of said protector to secure said clamp to said protector, and means for adjusting said gripping device to conform to shoe shanks of different widths.

5. A boot and shoe sole attachment including a flexible outer sole portion and an inner layer or lining portion of waterproof material, and lever actuated clamping mechanism at the end of the outer sole to secure the rear edge of the attachment in position 70 to the shoe shank, said inner layer or lining portion having a tongue extending beyond the sole portion and overlying the clamping mechanism in position to be pressed by the latter against the under surface of the shoe 75 shank to exclude moisture from entering the shoe by way of the shank.

In testimony whereof I affix my signature in presence of two witnesses.

EUGENE FULLER.
